UNITED STATES PATENT OFFICE

VIRGIL PARKINS, OF TIFFIN, OHIO

OIL-TEMPERATURE REGULATOR

Application filed May 10, 1928. Serial No. 276,718.

The present invention is directed to improvements in oil temperature regulators, more particularly designed for use in connection with automobile engines.

The primary object of the invention is to provide a device of this character constructed and arranged in such manner that the lubricating oil will be maintained at an even temperature either in warm or cold weather.

10 Another object of the invention is to provide a device of this character so constructed that the oil can be quickly heated in cold weather in order that it will quickly flow to the proper points to assure proper lubrication 15 thereof.

Another object of the invention is to provide a device of this character which is automatic in operation, the construction being such that the oil will be permitted to freely 20 circulate and be pumped to the proper bearing and will be maintained at an effective consistency to assure efficient lubrication.

Another object of the invention is to provide a device of this character which is simple in construction, efficient in operation, durable, and one which can be manufactured at a very small cost.

While the drawings illustrate a preferred embodiment of the invention it is to be understood that in adapting the means to meet specific needs and requirements the design may be varied and such other changes in the minor details of construction may be resorted to within the scope of the invention as 35 claimed, without departing from the spirit thereof.

For a full understanding of the invention and the merits thereof, reference is to be had to the following description and the drawings 40 hereto attached, in which,—

Figure 1 is a side elevation of an engine, parts broken away and showing the relative arrangement of the parts in connection therewith.

45 Figure 2 is a sectional view of the thermal unit.

Figure 3 is a sectional view on line 3—3 of Figure 2.

50 Figure 4 is a detail sectional view of the pump,

Figure 5 is a front elevation of the radiator.

Figure 6 is a fragmentary vertical sectional view through the same.

Figure 7 is a sectional view through the 55 exhaust pipe and gas controlling valve.

Figure 8 is a sectional view through the safety valve.

Figure 9 is a horizontal sectional view 60 through the heater.

Referring to the drawings, 1 designates a gas engine of conventional form, and 2 the radiator thereof, which differs from the usual radiator inasmuch as an oil radiator 3 is formed in the lower end thereof. The radiator has associated with the forward side thereof a plurality of shutters 4 which control the entrance of air through the passage 5, said shutters being pivotally connected by a rod 6 serving to simultaneously shift the shutters in a manner to be hereinafter described.

65 An oil pump 7 of the double gear type is connected with the crank case through a pipe 9 and as usual is operated by the shaft 10 driven by the cam shaft 11 of the engine, or in any other appropriate manner. The pump casing 12 has fixed thereto a valve casing 13 provided with a discharge 15 which leads to the crank case 8, said casing having a seat 15 which has engaged thereon a spring 16, the purpose of which will appear later. It will be of course understood 70 that the pump serves to force oil to the various bearings, as customary. Leading from the pump 7 to the oil radiator 3 is a pipe assembly 17 which carries a valve casing 18 in which is formed a seat 19, said casing having a cap 20 thereon and in which is adjustably 75 threaded the tubular stem 21.

80 Cooperating with the seat 19 is a valve 22, the stem 23 of which extends into the stem 21, there being a washer 24 engaged upon the stem 23 and encircling the stem 23 and interposed between the valve 22 and washer 24 is a coil spring 25, the tension of which is being obviously regulated, upon adjusting the stem 21.

85 A pipe 26 leads from the oil radiator to the 100

crank case 8 in order that the oil can freely circulate in the crank case and reservoir.

Associated with the bottom of the crank case is a heater 27 which comprises a housing 28, said housing having mounted therein a central partition 29 to provide a circuitous passage 30, there being baffles 31 in the housing to retard the flow of hot gas as it flows through the circuitous passage 30. 5
10 Leading from the housing is a pipe 32 which extends to the muffler, not shown, the exhaust gases from the exhaust manifolds 33 flowing through the pipe 34 to the housing 24 and from thence into the exhaust pipe 32, when 15 the valve plate 35 is open. The valve plate 35 closes the seat 36 formed at the juncture of the pipe 34 and main exhaust pipe 37, said plate being pivoted on a shaft 39 to one end of which is fixed a pinion 40 which is in 20 mesh with the teeth of the segment 41 pivotally mounted, as at 42, said segment having an arm 43.

A thermal unit 44 is employed and comprises a body 45 which is screwed in the wall 25 of the crank case 8 for disposition transversely within the crank case and in a position to be submerged in the oil. This body has a longitudinal chamber 46 in which is 30 located the thermal rod 47, the inner end of which bears against the closed end 48' of the chamber so that the expansive action of the rod will be outwardly. The outer end of the rod 47 is formed with a worm 48 which extends a short distance beyond the head 49 of 35 the body 45, said head being squared in order that the unit can be conveniently screwed into the crank case. The worm 48 engages the interior teeth 50 of the gear 51 in order that when the rod expands or contracts 40 rotary movement will be imparted to said gear. This gear has a collar 52 provided with an annular flange 53 which is engaged by the plate 54 fixed to the head 49 to maintain the gear against displacement, but at 45 the same time permits the same to rotate freely. Meshing with the gear 51 are the teeth of the segment 55 which is pivotally connected to the head 49, as at 56, said segment having an arm 57. This arm operates 50 in a slot 58 formed in the protective casing 59 bolted to the head 49.

The arms 43 and 57 of the respective segments are pivotally connected by a rod 60, the latter being connected to the shutter 55 controlling rod 6 by a rod 61.

It will be obvious that when the engine has been idle the oil in the crank case will be comparatively cold, especially in winter. In order to heat the oil quickly, the valve plate 35 may be opened manually by swinging the arm 43, whereupon the shutters 4 will close. The engine is started and the exhaust gas enters the heater 27 to heat the oil in the crank case 8 to a consistency suitable 60 for free circulation. The valve 22 remains seated until the pressure in the pipe assembly

17 is sufficient to unseat the same, whereupon the oil will be permitted to circulate through the oil radiator 3. When the oil reaches a temperature above that desired and effective, the thermal rod 47 will expand and rotate the gear 51, thus rocking the segment 55 and arm 57 which pulls upon the rod 60 and pushes upon the rod 61, whereupon the valve 35 will close and the shutters open, thus cutting off the exhaust to the heater and permitting air to pass through the passage 5 to cool the oil. If the temperature of the oil drops the rod 47 will contract, whereupon the valve 35 will open and the shutters close. In this manner the oil can be maintained at an even temperature. 75
80

Should the valve 22 fail to unseat from any cause, the pressure of the oil in the casting 12 induced by the pump will unseat the valve 16 and permit the oil to flow into the 85 crank case 8.

Any suitable means may be connected to the arm 43 in order that the same can be operated from the instrument board of a vehicle, when desired. Obviously after the engine is started the operation of the device 90 will be wholly automatic.

While I have illustrated and described the oil radiator for containing the surplus oil as being a part of the usual radiator, it will 95 be of course understood that it can be a separate unit, and that the heater can be an integral part of the crank case or may be in the nature of an attachment.

From the foregoing, it is thought that the 100 construction, operation and many advantages of the herein described invention will be apparent to those skilled in the art, without further description, and it will be understood that various changes in the size, shape 105 and proportion and minor details of construction, may be resorted to without departing from the spirit or sacrificing any of the advantages of the invention.

Having thus described the invention, I 110 claim:

1. In an oil temperature regulator for explosive engines, an oil radiator, a valve in the exhaust pipe of the engine, a heater, shutters associated with the radiator, a thermostat extended into the crank case of the engine and operable by the temperature of the oil for controlling the opening and closing of the valve to regulate the flow of exhaust gas to the heater, said thermostat also controlling the opening and closing of the shutters, as and for the purpose set forth. 115
120

2. In an oil temperature regulator for explosive engines, an oil radiator having shutters associated therewith, a heater associated with the crank case of the engine, a valve controlling the flow of exhaust gas from the exhaust manifold of the engine to the heater, a thermostat controlled by the temperature of the oil in the crank case, and an arm rock- 125
130

able by the expansion and contraction of the thermostat to alternately open and close the valve and shutters, as and for the purpose set forth.

5 3. In an oil temperature regulator for explosive engines, an oil radiator in which oil from the crank case circulates, a thermostat extended into the crank case, an arm rockable by a thermostat during the expansion and contraction thereof upon change of temperature of oil in the crank case, shutters associated with the radiator, a valve in the exhaust manifold pipe of the engine, and rods connecting the arm, valve and shutters, 10 for alternately opening and closing the valve and shutters, as and for the purpose set forth.

15 4. In an oil temperature regulator for explosive engines, an oil radiator having shutters associated therewith, means for circulating oil from the crank case of the engine into the radiator, a valve in the exhaust pipe of the engine, a thermal unit extended into the crank case of the engine and including a bar, 20 a gear associated with the bar and rotatable upon the expansion and contraction thereof, an arm rockable by the gear and having a rod extending therefrom and connected with the shutters, and a second rod connected with 25 the valve for alternately opening and closing the shutters and valve upon rotation of the gear.

30 5. In an oil temperature regulator for explosive engines including a heater for cooperation with the crank case of the engine, a valve controlling the flow of exhaust gas from the exhaust manifold to the heater, an oil radiator having shutters associated therewith, means for circulating the oil from the 35 crank case of the engine to the radiator, a thermostat extended into the crank casing and including a rod having a worm carried thereby, a gear connected on the worm, a segment in mesh with the gear and including an 40 arm, a rod pivotally connecting the shutters and arm, a second rod pivotally connecting the arm and valve, said gear being rotatable upon the expansion and contraction of the 45 rod for alternately shifting the first and second named rods for alternately opening and 50 closing the shutters and valve.

In testimony whereof I affix my signature.
VIRGIL PARKINS. [L. S.]
